UNITED STATES PATENT OFFICE.

HENRY A. HOUSE, OF BRIDGEPORT, CONNECTICUT.

DRINKING VESSEL.

1,117,848.

Specification of Letters Patent. Patented Nov. 17, 1914.

Application filed July 30, 1912. Serial No. 712,234.

To all whom it may concern:

Be it known that I, HENRY A. HOUSE, a citizen of the United States, residing in Bridgeport, in the county of Fairfield and State of Connecticut, have invented certain new and useful Improvements in Drinking Vessels, of which the following is a specification.

This invention relates to drinking-cups 10 made of paper or similar inexpensive material.

More particularly the invention relates to such cups as are formed from an integral disk of paper and have plaited side-walls 15 and are coated with waterproof material.

The purpose of the invention is to provide such a cup of pleasing appearance and cleanly and comfortable in use, and mainly a cup which will withstand strain and hold 20 its shape during use.

The invention consists of a cup including in combination an integral sheet of paper, a coating of waterproofing material and a beaded rim of waterproofing material.

25 In the accompanying drawing, Figure 1 is a perspective view of a drinking-cup embodying my invention, Fig. 2 is a vertical central section through the same on line 2—2 Fig. 3, Fig. 3 is a top view, Fig. 4 is a horizontal section on line 4—4 Fig. 2, the cup-wall and plaits thereof being shown without the waterproofing coating, Fig. 5 is a horizontal section on a larger scale, of a portion of the wall without the waterproofing coating, and Figs. 6 and 7 are vertical sections 30 through portions of the lip of the cup, on lines 6—6 and 7—7 respectively of Fig. 3.

Similar reference numerals indicate corresponding parts.

40 Referring to the drawings, the bottom 10 of the cup has a depressed portion 11 set inwardly of the annular extending portion 12. The sides of the vessel extend upwardly from this annulus 12 to the top of the vessel 45 where they terminate in the lip 13 of the vessel. Between the bottom and the lip the sides of the vessel are shaped in a curve 20 which viewed from the exterior of the vessel is convex and from the interior concave, 50 and which passes into a curve 22 forming the upper part of the vessel which is concave viewed from the exterior and convex viewed from the interior, these two curves forming together an ogee or reverse curve. By these 55 curves the strain caused by the outward

thrust of the liquid is efficiently taken up and the bulging of the vessel is prevented.

The vessel is formed from a single sheet of paper by plaiting the sides of the vessel, which takes up the surplus material, the same being folded as indicated, in tapering plaits 16, said plaits being of greatest width at the top of the vessel and tapering therefrom toward the bottom of the vessel where they disappear. The plaits are made of considerable number so as to distribute the reinforcing which they provide uniformly around the vessel. The plaits more or less cover the surface of the vessel and thereby reinforce the same and also provide vertical 60 ribs of three thicknesses of material, namely the outer fold 17, the intermediate fold 18 and the inner fold 19, which folds act by themselves by reason of the material in them, to give strength to the vessel, and by reason 65 of having the curved shape described they still further add to the strength of the wall.

In manufacturing, the sheet of paper is made wet so as to be easily formed, and the center part is depressed, and during simultaneous depressing and rotation of the forming tools the portion of the sheet outside of the base is plaited and given the shape shown in the drawing, the lower part being given the convex form and the upper 70 part the concave form, said curved portions being joined by a short, intermediate 75 straight portion, the outline of the whole conforming to the well-known ogee curve.

The folds of the plaits adhere by reason of 80 the sizing contained in the paper, which is rendered adherent by the dampness of the paper. When formed the cup while warm 85 is immersed in melted paraffin or like material which saturates and coats the paper 90 and waterproofs the same and at the same time further cements together the folds of the plaits forming the ribs. After the paraffin is thus added, the cup is allowed to dry with its bottom uppermost, whereby the 95 paraffin in melted state flows downwardly to the lip and forms a reinforcing beaded rim at the edge of the lip, which strengthens the same and thereby the entire cup, and by filling up inequalities in the edge renders the 100 same smooth and rounded, thus facilitating 105 the use of the cup for drinking. The beaded rim may assume different detail forms, as shown at 30, 31, in Figs. 6 and 7 respectively, and may be principally or entirely located at 110

either the inside or the outside of the lip, or on both sides.

The mechanism used for forming the cups constitutes no part of this invention.

5 By this improvement an extremely durable one-piece paper drinking-vessel is obtained, and the adaptability of paper for the manufacture of drinking-vessels and like receptacles is largely increased.

10 One embodiment of the invention has been shown, but it is obvious that the invention may be applied to receptacles of other kinds and for various purposes and to this end changes may be made in the construction 15 without departing from the spirit of the invention.

I claim:

1. A cup, including in combination, an integral sheet of paper, a coating of waterproofing material and a beaded rim of waterproofing material.

2. An integral paper cup having side walls comprising vertical sections alternately of one thickness and a plurality of 25 thicknesses of paper, an outer coating of waterproofing material and a beaded rim of waterproofing material.

3. An integral paper cup having side walls composed of vertical sections alter-

nately of one thickness and three thicknesses 30 of paper, a coating of waterproofing material rendering said side walls of uniform thickness throughout and a beaded rim of waterproofing material.

4. An integral paper cup having side 35 walls of vertical sections alternately of one thickness and a plurality of thicknesses of paper, said plurality of thicknesses being cemented together by the inherent sizing of the paper and said cup having an outer coating and a beaded rim of waterproofing material.

5. An integral paper cup of one integral sheet having its side walls plaited and alternately of one thickness and a plurality of 45 thicknesses of paper gradually increasing in size from the lower part of the cup to the lip thereof, and a waterproofing coating thereon of greatest thickness at the lip of the cup.

In testimony, that I claim the foregoing as my invention, I have signed my name in presence of two subscribing witnesses.

HENRY A. HOUSE.
